UNITED STATES PATENT OFFICE.

JAMES L. BALDWIN, OF CHICAGO, ILLINOIS.

PARCEL-CARRIER.

1,165,565.

Specification of Letters Patent. Patented Dec. 28, 1915.

Application filed April 25, 1910. Serial No. 558,085.

To all whom it may concern:

Be it known that I, JAMES L. BALDWIN, a citizen of the United States, residing at Chicago, in the county of Cook and State of Illinois, have invented a new and useful Parcel-Carrier, of which the following is a specification.

My invention relates to parcel carriers in which a basket is detachably connected to a suspended car arranged to travel on an elevated track and the objects of my improvements are first, to provide an automatic locking and unlocking device between the basket and the car; second, to prevent the throwing cord from getting entangled with the car; third automatically to lock the car at the end of the track, when the basket is detached; fourth, to provide a safety or double track wire; fifth, to make a simple and effective thrower guide; sixth, to make a simple, cheap and durable device, and other features to become apparent from the description to follow.

My invention comprises an elevated track preferably made of two wires stretched between two stations, a car to travel on said track, a thrower for the car, a guide for the thrower, guards for the thrower cord, a basket and means for attaching and detaching the basket to the car, all of said parts being of a novel construction.

To describe my invention so that others versed in the art to which it pertains can make and use the same; I have illustrated it on the accompanying two sheets of drawing in which:—

Figure 1, is a side elevation of one station with a car in position to be sent out, embodying my invention. Fig. 2, is an inverted 40 plan view of the basket crosshead; Fig. 3, is a detailed longitudinal section of the automatic locking mechanism on the car for the basket; Fig. 4, is a similar view showing the said locking device in an unlocked position 45 and Figs. 5, 6 and 7 are views similar to Fig. 3, showing modifications.

Similar reference characters refer to similar parts throughout the several views.

The support 7 is secured to the ceiling or other overhead frame and has its lower end held in position by the guy wire 8. Swivelled about the lower end of the support 7 is the bracket 9 provided with the laterally extending ears 10 and 11 and the depending 55 extension 12. The frame 13 is riveted or otherwise secured to the ear 10 and has one

arm 14 extending a considerable distance out from the support 7 above the track wires 15 and 16 which are secured to the frame 13 at 17 by means of the clip 18. The free end 60 of the arm 14 has secured to it a cross bar which has secured at each end a vertical tube 19 which are so arranged that the track wires 15 and 16 lie between the lower ends of said tubes 19. Each tube 19 has slidably 65 mounted therein a coiled spring 20 whose upper end is arranged to stop in its upward movement against the shoulder 21 inside the tube 19.

To the lower end of each spring 20 is 70 rigidly secured a stirrup 22 whose lower ends are connected by a cross bar 23 which is normally held in position by the action of the springs 20 some distance below the car 24 which is mounted to travel on the 75 wheels 25 which roll on the track wires 15 and 16. The sides of the car 24 are spaced apart to straddle the thrower mechanism to be described. The cross bar 23 can be lifted by compressing the springs 20 and to thus 80 lift said bar 23, one end of each of the cords 26 is secured to the stirrups 22 at 27 and from thence extend up in the spring 20, over pulleys 28 and 29, thence down to the coupling 30 to which both cords 26 are secured. 85 The cord 31 has its upper end secured to the coupling 30 and extends down through guide 32 provided on extension 12 and down within reach of the operator. It will be seen that a downward pull on cord 31 will 90 pull up on the stirrups 22 and compress the springs 20. The basket not shown is provided with the upward extending bails 33 which are rigidly secured to the basket crosshead comprising the elongated open 95 frame 34 and the center cross bar 35 by means of which the basket is attached to the car 24. The frame 34 is provided with the two depending pins, 36 arranged to take into coöperating holes provided in the cross bar 23 when the said cross bar 23 and basket bracket are brought together. One of the pins 36 is provided with a catch which is engaged by a spring pressed latch 36' pivotally mounted on the bar 23, thus retaining 100 the basket crosshead in position on the frame 34. The upper end of the stirrup 22 is provided with a hook shaped extension as shown in Fig. 1, which is arranged above the path of the basket crosshead so as to 110 contact with the said crosshead when the stirrup is hit with considerable force and

moved laterally by the impact of the incoming car, thus preventing the cross bar 23 from swinging laterally out of registering position with the pins 36.

The car 24 is provided at either end with a spring pressed pivoted latch 37 arranged to engage the hook 38 when the car comes in to the station and prevent the said car from rebounding away from the station. The hook 38 is mounted on the end of a rod 39, mounted to slide in a perforation provided in the extension 12, and a buffer spring 40 is interposed between the hook 38 and the extension 12 to absorb the shock of the incoming car. A short cushion spring 41 is provided to counteract spring 40. The hook 38 is retained in proper position in the path of the car latch 37 by having a perforated extension 42 slidably mounted on the flat or angular rod 43 connected at one end to the ear 11 and at the other end to the bracket 44 which is clamped to the lower track wire 16. An arm 45 of the bracket 13 is secured to the rod 43 at 46, thus securing the bracket 13, the track wires 15 and 16, the bracket 44 and the rod 43 together to lie in the same vertical plane.

A thrower 47 for the car is mounted to slide on the rod 43 and has attached thereto for the purpose of operation one end of the cord 48 which extends from there out around pulley 49 pivoted in bracket 44, then back over pulley 50 pivoted in arm 45, and thence down around pulley 51 pivoted in hand block 52, thence up over pulley 53 pivoted in extension 12 and thence down to the hand block 52 to which its other end is secured so that when the hand block 52 is pulled down the thrower 47 will be pulled along to the right as viewed in Fig. 1, and if the car 24 is in position as shown in said Fig. 1, the thrower 47 will engage the upward extension 54 of the latch 37 and swing said latch about its pivot so as to disengage it from the hook 38 and the further movement of the thrower 47 will force the car 24 out along on the track. When the car is returned to the station it will engage the thrower 47 and return it to its normal position as seen in Fig. 1, and the latch 37 will catch in hook 38. The rod 43 is made flat or angular in cross section so as to prevent the thrower 47 which is strung thereon from tilting or turning on said rod 43.

The basket with its crosshead is made detachable from the car 24 and to prevent the accidental throwing out of the car 24 when the basket is detached therefrom, I provide on the basket crosshead frame 34 an extension 55 made on an incline to serve as a cam for lifting the free horizontal end of lever 56, which is loosely pivoted to the bumper 38, when the car is at the station with a basket attached thereto. When the basket with frame 34 is removed from the

car, force of gravity will cause the horizontal end of lever 56 to move down the hook end to swing to the right as viewed in Fig. 1, above the latch 37 and lock said latch against removal from the hook 38. Thus the car cannot be thrown out or removed from the station when there is no basket attached thereto. The extension 54 of the latch 37 is extended up to have its extremity pass very close to the extension 57 on the car frame so as to prevent the thrower cord 48 from getting entangled with the latch 37 or other parts of the car.

The mechanism provided for automatically locking and unlocking the basket to and from the car is best illustrated in Figs. 3 and 4 and comprises the main locking lever 58 pivoted at 59 to the car 24, the secondary locking lever 60 pivoted at 61 to the lever 58 and the releasing lever 62 pivotally and slidably mounted on the pin 63 secured in the secondary locking lever.

The car 24 is constructed of two side plates provided with two pairs of depending lugs 64 and the levers 58, 60 and 62, are located between these two side plates. As seen in Fig. 3 when the basket is lifted by the elevator, *i. e.*, the stirrups 22 and ropes 26, the cross bar 35 of the basket crosshead frame 34 passes up between the lugs 64, engages and lifts the lever 58 about its pivot 59, lifting lever 60 until its lower end provided with the notch 65 falls by gravity into position engaging the pin 66 secured in the lugs 64, and the hook shaped end 67 of lever 62 will fall by gravity down over the lug 68 provided on lever 60 adjacent the notch 65, thus locking the notch 65 of lever 60 against removal from the contact with pin 66, by the hook 67, and holding the levers 58 and 60 in their proper position to support the cross bar 35 as clearly seen in Fig. 3. As the cross bar 35 of the elevator descends it engages and depresses the free end of lever 62 and swings it about the lug 68 as a pivot until it passes the same, when the lever 62 will again resume its normal position with its free end in the path of cross bar 35, as seen in Fig. 3. The lever 62 is slidably mounted on the pin 63 by means of a slot 63' for the purpose of permitting said lever 62 to be swung about the lug 68 as a pivot, and a compression spring 63'' is provided to hold the lever 62 yieldingly down and against the pin 63 and the lug 68 and pin 63. It will be seen that gravity may be depended on for this purpose, but I prefer to use a spring. When the basket is thus locked to the car 24 and the elevator is lifted by a downward pull on the rope 31, the cross bar 35 of the elevator will engage the free end of lever 62, swing the same up about its pivot 63, lift the hook 67 up out of the path of the lug 68 and pin 66, the tail end 70 of lever 62 will take against the

extension 71 on lug 64 and act as a pry to move the lower end of lever 60 to the right as viewed in Fig. 3, out of engagement with the pin 66, thus permitting the lever 58 to swing down about its pivot 59 and releasing the cross bar 35 from the car as seen in Fig. 4.

From the description given it will be understood that repeated raising and lowering 10 of the elevator will alternately lock and unlock the basket to and from the car 24.

In Fig. 5, is shown a modification in which the secondary lever 72 is pivotally connected to the hook portion 69 of lever 15 58 and the releasing lever 74 is pivotally and slidably connected to the pin 75 secured in lever 72. The lever 74 is provided with an irregular slot 76 through which the pin 77 secured in the lugs 64 extends. The operation 20 of this structure is similar to that of the structure shown in Figs. 3 and 4, *i. e.*, repeated raising and lowering of the elevator will alternately lock and unlock the basket to and from the car 24.

25 In Fig. 6, I have illustrated another modification in which the secondary lever 78 is pivotally connected at 79 to the hook portion 69 of lever 58 and the releasing lever 80 is pivotally and slidably mounted on pin 81 secured in lever 78 and cooperates with pin 82 secured in lugs 64. The operation of this is so similar to the device shown in Figs. 3 and 4 that it will not be necessary to describe the same.

35 In Fig. 7, still another modification is shown in which the main locking lever 83 is pivoted at 84 to the lugs 64 and is provided with the hook shaped part 85 and the lower end carrying the pin 86 about which is 40 pivotally and slidably mounted the locking and releasing lever 87 which is provided with the hook 88 which when in a locked position engages the pin 89 secured in the lugs 64. In this construction there is no 45 secondary lever between the locking and releasing lever and the main locking lever, but the locking and releasing lever 87 is connected directly to the main locking lever 83. It will be noted that when the parts are in 50 a position supporting the cross bar 35 on the hook shaped portion 85 as seen in Fig. 7, that the weight of the basket is supported by the pivot 84, and to assist in supporting said basket, the lower side of lever 83 may 55 be made on an arc struck from the pivot 84 to rest on the pin 89. The operation of this device is similar to the operation of those constructions described above.

Having thus fully described my invention 60 what I claim as new and desire to secure by Letters Patent of the United States is:

1. In a parcel carrier, a car to travel on a suspended track, a basket crosshead, and 65 means for automatically locking and un-

locking said basket crosshead to and from said car comprising a main pivoted locking lever, a secondary locking lever pivoted to said first named lever and a releasing lever attached to said second named lever. 70

2. In a parcel carrier, a track, a car to travel on said track, a basket crosshead, and means for automatically locking and unlocking said basket crosshead to and from said car comprising a pivoted locking lever 75 and a combined locking and releasing lever operatively connected to said locking lever to move with it.

3. In a parcel carrier, a track, a car to travel on said track, a basket detachably 80 secured to the car provided with a suitable bracket, an elevator for the basket provided with a suitable stirrup whose lower end is arranged to register with depending lugs on the basket bracket and an extending hook 85 on the upper part of the stirrups to engage the said basket bracket when the stirrup is moved laterally by the impact of the car and prevent the elevator stirrup from being forced out of registering position with the 90 basket bracket.

4. In a parcel carrier, a track, a car to travel on said track, a basket crosshead, a bumper hook at the end of the track to retain the car and a locking lever pivoted to 95 said bumper hook to lock the car on the hook in the absence of the basket crosshead.

5. In a parcel carrier, a track, a car to travel on said track, a basket bracket detachably connected to the car, a bumper hook at 100 the end of the track to retain the car and a locking lever pivoted to said bumper hook, and actuated by the basket bracket, to lock the car on the hook in the absence of the basket. 105

6. In a parcel carrier, a track comprising a wire, a support for the track wire, a car to travel on said track, a bar rectangular in cross section having one end secured to the track wire remote from the track wire support, a thrower for the car provided with a rectangular perforation threaded onto said bar and arranged to slide thereon and means for operating said thrower. 110

7. In a parcel carrier, a track comprising 115 a wire, a support for said wire, a car to travel on said track, a bar rectangular in cross section arranged below and parallel to said track having one end secured to said wire support and the other end secured to the track wire remote from said wire support, a one piece thrower for the car provided with a rectangular perforation threaded onto said bar and arranged to slide thereon and a pull cord attached to said thrower 120 for operating the same.

8. In a parcel carrier, a track comprising one upper and one lower wire, a bar angular in cross section secured to said lower track wire to lie parallel thereto, a basket to be 130

- 4 attached to and detached from the car, an elevator at the end of the track for the basket, a car to travel on said track provided with spaced slides arranged to straddle the 5 angular bar and be guided thereby against lateral movement to enter its position at the elevator and a thrower for the car to slide on the angular bar and held against rotation thereby.
- 10 9. In a parcel carrier, a track, a car to travel on said track, a pivoted latch at the end of the car to hold the car at the station, an upward extension on said latch to release the car from the station, a thrower cord 15 passing through between the spaced sides of the car, and an extension on the car frame terminating close to the free end of the extension on the latch to prevent the thrower cord passing between said two extensions.
- 20 10. In a parcel carrier, a track wire, a framing secured below said track wire comprising a bar angular in cross section secured to the vertical track wire standard, a car to travel on said track having spaced 25 sides to pass on each side of said framing, a pivoted latch on said car, pulleys carried on said framing and a propeller cord passed over said pulleys, a thrower for the car attached to said cord and mounted to slide on said angular bar of the framing and guided thereby to engage and release the latch on the car and to propel said car along the track wire.
- 30 11. In a parcel carrier, a track wire, a framing below said track wire secured at one end to the track wire support and at the other end to the track wire remote from the track wire support, said framing comprising a bar angular in cross section, a car to travel on said track having spaced sides 35 to pass on each side of said framing, a pivoted latch on said car, pulleys carried on said framing and a propeller cord passed over said pulleys, a thrower for the car attached to said cord and mounted to slide on said angular bar of the framing and guided thereby to engage and release the latch on the car and to propel said car along the track wire.
- 40 45 In testimony whereof, I have signed my name to this specification in presence of two subscribing witnesses this 15th day of February, 1910, at Chicago, Illinois.
